SHUTTLES FOR LOOMS FOR WEAVING

William Holt, Todmorden, England

Application January 14, 1959, Serial No. 786,759

Claims priority, application Great Britain March 7, 1958

7 Claims. (Cl. 139—207)

This invention relates to improvements in shuttles for looms for weaving, and more particularly to shuttles for automatic looms of the type in which a pinn is mounted in the shuttle between spring jaws of a stirrup member.

In shuttles for automatic looms in which a cop changing mechanism is provided for automatically ejecting an empty cop and replacing it by a full cop the head of the pinn is formed with rings which engage serrated spring jaws carried by a stirrup member secured in the shuttle by a bolt passing from side to side of the shuttle through a cylindrical bore in the member. It has been found that the constant vibration of the shuttles and the force exerted on the jaws during changing the cop causes the stirrup member to become loose in the shuttle due to wear on the bolt and shuttle.

The object of the present invention is to provide means for securing the stirrup member more securely in the shuttle.

According to the invention the stirrup member is formed with an angled non-cylindrical bore to receive correspondingly shaped locking blocks engaging a recess in the shuttle head.

The invention will be described with reference to the accompanying drawings:

Figure 1 is an exploded perspective view of a shuttle nose and a stirrup member having a locking block assembly secured thereto according to one embodiment of the invention.

Figure 2 is a plan view partly in section of the shuttle nose assembly of Figure 1;

Figure 3 is a perspective view of another form of stirrup member and locking block;

Figure 4 is a plan view partly in section showing a shuttle nose assembly according to a further embodiment of the invention;

Figure 5 is a perspective view showing a stirrup member and locking block according to still another embodiment of the invention;

Figure 6 is a perspective view showing a stirrup member and locking block according to a still further form of the invention;

Figure 7 is a perspective view of a locking block according to still another embodiment of the present invention.

A shuttle A is provided with a stirrup member B having serrated spring jaws b for engaging a pinn in known manner.

The stirrup member B is formed with an angled non-cylindrical bore b¹ to receive a correspondingly shaped locking block C for securing the member in the shuttle head A.

The bore b¹ in the stirrup member B is substantially square with one side tapering from the reed side a of the shuttle. The stirrup member B is secured in position in the shuttle head A by the block C which is formed with a tapered face to engage the taper in the bore b¹ and a narrower block C¹ formed with parallel sides which

2

are pressed into the bore b¹ to engage one of the parallel sides of the block C and the bore b¹.

The larger end of the block C enters a recess or cavity a¹ in the shuttle head A and is prevented from emerging on the reed side a of the shuttle by a portion of the shuttle defining an end wall surface for the cavity a¹. Referring to Figure 2, the cavity a¹ has a tapered wall surface adjacent the nose of the shuttle A which corresponds to the tapered wall surface of the block C so that the cavity a¹ is smallest at its entrance. In the assembly of the locking blocks in the cavity, the large block C is first inserted into the cavity a¹ and is dimensioned so that the wider end just clears the entrance to the cavity a¹. This block C is then moved into the position shown in Figure 2 and the narrower block C¹ is thereafter inserted through the entrance of cavity a¹ to establish a snug fit of the locking block in the cavity a¹. A locking pin or screw c may be employed to secure the block C¹ in position. The end of the block C¹ may be bent over to receive the pin c (Fig. 2) which screws into the block C.

The head of the stirrup member B may be solid (Fig. 2) or may be formed from a strip of metal bent to provide the jaws b (Fig. 6) and may be provided with a resilient or other packing D¹ between the jaws at the head end (Figs. 3 or 6) held in position by a jaw cover plate D secured to the shuttle by a bolt d passing through a hole d¹ in the plate D or it may be secured by a screw. The bolt d passes also through a hole a² in the shuttle head (Figs. 1 and 5).

The block C¹ may be recessed to be locked by the bolt d (Fig. 5) or a hole c² may be formed in the block C¹ to receive a tongue d² on the packing D¹ (Figs. 3 and 4) or the block C may be grooved (Fig. 6) to receive a recessed end of the packing D¹ or a projecting portion thereon (Fig. 7).

A variation in the position of the tapered block may be used for alignment of the pinn in the shuttle.

The bore b¹ in the stirrup member B may be square, oblong or of other non-cylindrical form and taper from the inside towards the side of the shuttle remote from the reed.

The locking blocks CC¹ may be of metal, hard wood or of artificial or synthetic material.

In order to dismantle the stirrup member B a small bore a³ may extend through the shuttle from the reed side a to receive a tool a⁴ by which the block C¹ may be driven out of cavity a¹ after which the block C¹ may be lifted out.

The shock and pressure on the jaws B when the automatic loom is changing the pinn is better resisted by the corners and planes against the walls of the slot than is the case where a round bolt is used which may turn round and the nut work loose on the thread, or the jaws may move around the bolt and wear, thus causing the weft to break while weaving because the pinn is out of alignment. The locking blocks CC¹ cannot work out at the back of the shuttle because of the solid wooden wall.

A lining may be provided in the shuttle to receive the blocks if desired.

The arrangement may be employed in non cop changing shuttles where the pinn is mounted on a pivoted skewer and turned down into the weaving position to engage the jaws.

65 I claim:

1. A shuttle for looms for weaving comprising a shuttle nose having a tapered recess therein, a stirrup member for securing a pinn in position in the shuttle having a tapered passage therethrough and a locking block having a tapered surface corresponding to the taper of said recess and said passage for securing the stirrup

member in the shuttle nose to prevent movement of the stirrup member therein.

2. A shuttle for looms for weaving comprising a shuttle nose having a first tapered recess and a second recess intersecting said first recess, a stirrup member for securing a purn in position in the shuttle and having a portion projecting into said second recess, said portion having through tapered passage means disposed in said first recess wherein the taper of said passage means is in the same direction and corresponds to the taper of said first recess and a locking block extending into said first recess and through said passage means, said locking block having a tapered wall surface corresponding and in bearing relation to the tapers of said passage means and said first recess for securing the stirrup member in the shuttle nose to prevent movement of the stirrup member therein.

3. A shuttle for looms for weaving comprising a shuttle nose having a tapered recess therein, a stirrup member for securing a purn in position in the shuttle having a through tapered passage disposed in said recess, locking block means for securing the stirrup member in the shuttle nose to prevent movement of the stirrup member therein and comprising a locking block and a rectangular shaped block projecting into said recess and through said passage in juxtaposition bearing relation to each other, said locking block having a taper surface extending in the same direction as and adjacent to the tapered surface of said recess.

4. A shuttle for looms for weaving comprising a shuttle nose having a tapered recess therein, a stirrup member for securing a purn in position in the shuttle having a tapered through passage disposed in said recess, means for securing the stirrup member in the shuttle nose to prevent movement of the stirrup member therein and comprising a tapered locking block having a direction of taper cor-

responding to the direction of taper of said recess and said passage and a rectangular locking block adjacent said tapered locking block, said blocks extending into said recess and through said passage, a jaw cover plate and a bolt for securing the jaw cover plate and locking the rectangular block in the shuttle head.

5. A shuttle for looms for weaving comprising a shuttle nose having a tapered recess therein, a stirrup member for securing a purn in position in the shuttle having a tapered through passage, means for securing the stirrup member in the shuttle nose to prevent movement of the stirrup member therein and comprising a tapered locking block having a direction of taper corresponding to the direction of taper of said recess in said passage and a rectangular locking block adjacent said tapered locking block, said blocks extending into said recess and through said passage, a jaw cover plate and a bolt for securing the jaw cover plate in the shuttle, a packing member and a tongue thereon for entering between the stirrup member to engage in the rectangular block.

6. A shuttle for looms for weaving as in claim 5 wherein means are provided in at least one of said blocks for defining at least one groove to receive at least one tongue on the packing member.

7. A shuttle for looms for weaving as in claim 5 in which a bore is formed in the shuttle nose to receive a tool for the removal of the blocks.
